Attorney

UNITED STATES PATENT OFFICE.

STEPHEN HARDER, OF WASHINGTON, DISTRICT OF COLUMBIA.

SIGNAL MEANS FOR RECORD-STRIP COMPOSING MACHINES.

Application filed November 7, 1922. Serial No. 599,613.

To all whom it may concern:

Be it known that I, STEPHEN HARDER, a citizen of the United States, residing at Washington, in the District of Columbia, 5 have invented certain new and useful Improvements in Signal Means for Record-Strip Composing Machines, of which the following is a specification.

My invention relates to signal means for 10 use in connection with a record strip composing machine, for advising the operator when a line, or section or sections of a line are nearing completion.

An important object of the invention is to 15 provide a device of the above mentioned character, which is in the nature of an attachment, and adapted to be installed upon, or used in connection with the record strip composing machine of the type shown in 20 Letters Patent No. 944,405, issued to J. S. Bancroft and M. C. Indahl, under date of December 28, 1909.

A further object of the invention is to 25 provide a device of the above mentioned character, which may be used in connection with the record strip composing machine, of the character stated, without materially altering the construction of the machine.

As is well known, in the use of the record 30 strip composing machine, commonly known as the monotype machine, such as is shown in Patent No. 944,405, when the line is nearing completion, and the pointer is nearing the end of the scale, a pin carried by the em rack, engages and trips a lever, whereby 35 a bell is sounded, and a light is made to glow in the justification cylinder or scale, thus apprising the operator that the end of the line is being approached.

While this signal means is of considerable 40 aid to the operator, yet there are disadvantages encountered in connection with the same. The signal is not adjustable and hence the signal is fixed with respect to a line of a given length. Further, it is customary in the operation of these record strip composing machines to set in one line or row 45 a plurality, such as three, line sections, included in three vertical columns. The operator must watch the pointer and scale, having marked upon the scale the end of the respective line sections or columns, in order 50 that he may retain the edges of the column straight. In the absence of any signaling means at the end of the line sections or columns, it frequently happens that the columns

will not be properly straight, at the edge thereof, the signal not being operated until the end of the line, at the edge of the last column. 60

In accordance with my invention I provide adjustable means embodying trips which may be set into the active position, at various points along the em rack, depending upon the width of the line sections or columns, and these trips coact with means arranged to operate the trip lever, which in turn will operate the signal means, upon the machine, as it now does, when the usual pin on the em rack engages the trip lever. By 70 this means, a signal will be given as the end of each line section or column is approached, and these signals are auxiliary to the usual signal of the machine, and in no way interfere with the operation of the usual signal. 75 Further, the trip elements carried by the em rack are adjustable, and hence the device is flexible so that the signals will be properly given, in connection with line sections or columns of varying lengths. 80

I also contemplate the provision of an attachment which is adjustable, to operate a signal at the end of a line, line section, or column, which may vary in length. This attachment may be applied to the record type 85 composing machine of Patent No. 944,405 without materially altering the construction of the same.

Other objects and advantages of the invention will be apparent during the course 90 of the following description.

In describing those parts of the machine which are old and well known, shown in Patent No. 944,405, the numerals appearing in brackets are those used to designate the 95 same parts in Patent No. 944,405.

In the accompanying drawings forming a part of this specification, and in which like numerals are employed to designate like parts throughout the same. 100

Figure 1 is a perspective view of the signal attachment, embodying my invention, showing the same in use.

Figure 2 is a side elevation of the swinging tripped member, 105

Figure 3 is a transverse section through the em rack, showing a modified form of adjustable trip, and,

Figure 4 is a similar view showing a still different form of adjustable trip. 110

Attention being called first to Figures 1 to 4 inclusive, the numeral 10 (14) design-

nates the em rack or line scale rack, operating within the guide 11. This guide carries the line scale 12, with the pointer 13 traveling in proximity of the line scale. The numeral 14 (7) designates the units wheel, which advances the em rack 10. The numeral 15 is a vertical stationary rod. 16' (101) designates the latch or lever which trips or actuates the signal means. In the claims, 10 this element will be referred to as the signal actuating means. It is intended that this term cover any means of operating an audible or visual signal or both. As shown in Patent No. 944,405, Figure 28, the lever 16' (101) operates the means to ring a bell. These elements are all old and well known in the art, and are identical with those shown in Patent No. 944,405, to which reference 15 may be had to a disclosure of the complete machine.

In accordance with my invention I provide a stationary bracket 16, having a slotted foot 17, to engage about the rod 15, and clamped thereto by nut or nuts 18 or 20 the like. At its upper end, this bracket carries a forwardly projecting horizontal shaft 19, rigidly secured thereto. Freely pivoted upon the forward end of the shaft 19 is a 25 forked trip member 20, held against lateral displacement by nuts 21 and 22, or by any other suitable means. The swinging movement of the member 20 to the right, is limited by an adjustable stop 20', apertured to receive the shaft 19, and clamped between the nuts 22. The member 20 is provided with 30 depending fingers 23 and 24, which are spaced, and are disposed upon opposite sides of the em rack 10, as shown. These fingers 35 preferably taper downwardly, as shown. The finger 24 is arranged in advance of the latch or lever 16', to engage therewith, and swing this latch upon its pivot. 40

The finger 23 is arranged upon the forward side of the em rack 10 outwardly of the path of travel of trips 25, when these trips are in the inner inactive position. In Figures 1 and 2, these trips are shown in the form of screws, for their ready adjustment. The screws are equidistantly spaced, and their distance apart may vary, as may 45 be found advantageous. The selected screws are unscrewed sufficiently, so that they will project forwardly in the path of travel of the finger 23, and hence trip the member 20. If a line is being set, in three sections or 50 columns, three of the selected screws will be adjusted outwardly, so that the member 20 will be actuated as the completion of the line section or column is neared, and hence a signal will be given at this time.

Instead of providing the screw-threaded openings 26 and the screws 25, these elements may be dispensed with, and I may 55 provide the forward side of the em rack 10 with a longitudinal groove 27, trapezoidal

in cross section. This groove may extend from the leading end of the em rack to the pointer 13. I then provide any suitable number of trips 28, having trapezoidal heads 29, slidable in the groove 27. The trip 29 carries a nut 30 screw-threaded upon its outer end, and a coil spring 31 surrounds the trip and engages between the nut 30 and the forward face of the em rack. The spring 31 provides sufficient frictional engagement 70 between the head 29 and the groove 27, whereby the trip will be held in the selected position, upon the em rack, when shifted thereto. If a line is being set in three sections or columns, three of the trips 28 would 75 be employed, properly adjusted upon the em rack, at the points near the completion of each line section or column.

In Figure 4 I have shown a further modification of trip. The numeral 32 designates the trip, provided at its rear or inner end with diverging resilient ears 33, fitting within the groove 27, and adapted to frictionally engage with the side walls of the groove, to hold the trip 32 in place within 80 the groove, when adjusted therein, to a selected position.

In view of the foregoing description, it is thought that the operation and use of the forms of the invention, should be readily 95 understood, and that no further description, is deemed necessary.

It is to be understood that the form of my invention herewith shown and described is 100 to be taken as a preferred example of the same, and that various changes in the shape, size, and arrangement of parts may be resorted to without departing from the spirit of my invention, or the scope of the subjoined claims.

Having thus described my invention, I claim:

1. The combination with the longitudinally moving em rack of a record strip composing machine, of a plurality of adjustable trips arranged upon said rack, a movable member having a part thereof arranged in the path of travel of said trips, and a signal actuating element operated by said movable member.

2. The combination with the longitudinally moving em rack of a record strip composing machine, of a signal actuating element arranged upon the rear side of said rack, a plurality of trips adjustably mounted upon the forward side of said rack and adapted to assume proper spaced positions, and a movable member having a part thereof extending upon the forward side of said rack to engage with said trips and also having a part extending upon the rear side of said rack to engage with the signal actuating element.

3. The combination with the longitudinally moving em rack of a record strip com-

posing machine, of a pivoted signal actuating lever arranged upon the rear side of the rack, a stationary support, a rod carried by the support and projecting forwardly over said rack, a member pivoted upon said rod above the rack and having its lower end forked to provide spaced fingers disposed upon opposite sides of said rack, one finger being arranged to engage the pivoted lever, and a plurality of trips carried by the opposite side of the rack.

4. The combination with the longitudinally moving em rack of a record strip composing machine, of a movable signal actuat-

ing element arranged upon one side of said rack, said rack being provided upon its opposite side with a plurality of spaced screw-threaded openings, a corresponding number of stops having parts thereof screw-threaded into said screw-threaded openings and adapted to be adjusted laterally with relation to said rack, and a pivoted member having a finger arranged to coact with said stops and another finger to actuate said signal actuating element.

In testimony whereof I affix my signature.

STEPHEN HARDER.
